US00D608355S

(12) **United States Design Patent**
Fahlgren et al.

(10) **Patent No.:** **US D608,355 S**
(45) **Date of Patent:** **** Jan. 19, 2010**

(54) **HANDSET FRONT COVER**

(75) Inventors: **Anton Fahlgren**, Copenhagen (DK);
Thomas Ulrich Christiansen,
København Ø (DK)

(73) Assignee: **Nokia Corporation**, Espoo (FI)

(**) Term: **14 Years**

(21) Appl. No.: **29/333,350**

(22) Filed: **Mar. 6, 2009**

(51) **LOC (9) Cl.** **14-03**

(52) **U.S. Cl.** **D14/248**

(58) **Field of Classification Search** **D14/137, D14/138 R, 138 AA, 138 AB, 138 AD, 138 C, D14/138 G, 143-144, 147-148, 156, 218, D14/247-248, 341-347, 390, 399, 455-456, D14/496; D16/208, 219; D21/329, 331, D21/333, 517; 348/14.01-14.02; 361/814; 379/433.01-433.13; 455/90.3, 556.1-556.2, 455/566, 575.1, 575.3, 575.4; D13/164, D13/168, 103, 119; 439/165; 343/702; 345/167, 345/168, 169**

(57) **CLAIM**

The ornamental design for a handset front cover, as shown and described.

DESCRIPTION

FIG. 1 is a perspective front view of a handset front cover showing our new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken line showing of the environmental structure of the handset in FIGS. 1-6 is for illustrative purposes only and forms no part of the claimed design.

1 Claim, 3 Drawing Sheets
